UNITED STATES PATENT OFFICE.

ELBERT J. GILMORE, OF LOWELL, MASSACHUSETTS.

LAMP ATTACHMENT.

SPECIFICATION forming part of Letters Patent No. 726,525, dated April 28, 1903.

Application filed July 2, 1902. Serial No. 114,078. (No model.)

To all whom it may concern:

Be it known that I, ELBERT J. GILMORE, a citizen of the United States, and a resident of Lowell, county of Middlesex, State of Massachusetts, have invented an Improvement in Lamp Attachments, of which the following description, in connection with the accompanying drawings, is a specification, like letters on the drawings representing like parts.

This invention has for its object the production of a novel lamp attachment whereby the filling of an oil-lamp may be readily and quickly effected without interference by the depending portion of the wick, the burner being so mounted on or connected with the lamp-bowl or oil-reservoir as to be swung back for filling purposes, at such time the wick being moved over close to one side of the filling-opening. I have also provided means for effectually preventing the escape of oil or vapor between the fixed and movable parts or members of the connection between the burner and the lamp-collar.

The various novel features of my invention will be hereinafter described, and particularly pointed out in the following claims.

Figure 1 is a side elevation of a lamp attachment embodying one form of my invention, the burner being swung back for the purpose of filling the lamp-bowl. Fig. 2 is a front elevation thereof; and Fig. 3 is a vertical sectional view of the device on the line xx , Fig. 2, the burner being shown, however, as shut down or closed in normal position.

The lamp-bowl or oil-reservoir A, shown only in part, the lamp-collar A^x , permanently secured thereto surrounding the filling-opening and having an internal screw-thread a^x , Fig. 3, and the burner comprising the tubular or sleeve-like body B, deflector or hood B' , and wick-tube B^2 , may be and are all of substantially usual or well-known construction. In my present invention, however, the lower end of the wick-tube is extended very slightly

beyond the lower face of the bottom b' of the body, as at b^2 , and said bottom is provided with a series of external annular corrugations b^x adjacent its periphery, for a purpose to be described, said corrugations being shown in Figs. 2 and 3. The corrugations may be formed by stamping, pressing, or in any other suitable or convenient manner. A

coupling sleeve or connection C has secured to it a hinge-loop or similar device c to receive a pintle b , attached to the body of the burner, the latter being provided at a point substantially diametrically opposite the hinge with a spring-catch b^3 to coöperate with a pin or projection c^3 on the coupling C. The lower end of the latter is externally screw-threaded at c^x to coöperate with the thread a^x of the lamp-collar, and thereby connect the latter and the coupling in a strong and rigid manner. At its upper end I have shown the coupling C provided with an inturned flange c^5 , which is annularly corrugated in such manner that the ribs or grooves thereof register with or are opposite the grooves and ribs, respectively, of the corrugated portion b^x of the burner-body, as clearly shown in Fig. 3, when the burner is in closed or operative position. At such time the spring-catch b^3 is engaged and held by the projection c^3 , and the two sets of annular corrugations seat squarely and closely one upon the other, so that an oil and vapor tight joint is provided between the body of the burner and the coupling, preventing any leakage of oil to the exterior of the attachment and preventing escape of vapor from the lamp-bowl.

To fill the lamp, the catch b^3 is released by the finger and the burner is swung back on the hinge connection between it and the coupling C, and the edge of the chimney-holder B^3 by engagement with the exterior of the lamp-collar, as shown in Fig. 1, maintains the bottom b' of the burner-body substantially vertical and at the extreme edge of the coupling C. This, in connection with the short end of the wick-tube, brings the depending portion of the wick close to the side of the coupling, leaving the greater portion of the opening therethrough free and unobstructed for filling; but the wick is held away from the interior of the coupling, so that oil will not be deposited thereupon.

I have shown one practical embodiment of my invention, and the same may be modified or varied somewhat in different particulars without departing from the spirit and scope of my invention.

Having fully described my invention, what I claim as new, and desire to secure by Letters Patent, is—

1. A lamp attachment comprising a burner, a coupling pivotally connected therewith and having means for attachment to the collar of a lamp, and oppositely-arranged, annular corrugations on the body of the burner and the coupling, respectively, to coöperate when the burner is closed and form a tight joint between it and the coupling. 30
2. A lamp attachment comprising a burner, a coupling pivotally connected therewith and having means for attachment to the collar of a lamp, annular grooves and ribs on the upper end of the coupling, and opposed ribs and grooves on the bottom of the body of the burner, to coöperate with each other when the burner is closed and form a vapor and oil tight joint, and a device to lock the burner and coupling together when closed. 35
3. A lamp attachment comprising a burner having a tubular body with a closed bottom provided with peripheral, annular corrugations on its under face, a tubular coupling member having means for attachment to a lamp-collar, a hinge peripherally connecting the upper end of the coupling and the burner-body, and an inturned, annularly-corrugated flange at the upper end of the coupling, the 40 ribs and grooves whereof register with the grooves and ribs, respectively, of the annular corrugated portion of the burner-body 45 when the burner is closed, to form a tight joint between it and the coupling.
4. The combination with a threaded lamp-collar, of a tubular coupling screwed thereto, and having its upper end annularly corrugated, a burner having its tubular body hinged to the coupling, a wick-tube projecting slightly beyond the closed bottom of the burner-body, annular corrugations at the periphery of the bottom, to coöperate with the upper end of the coupling when the burner is closed, and means to coöperate with the lamp-collar and maintain the burner in position when open to move the depending part of the wick toward the side of the coupling, 45 leaving an unobstructed central passage therethrough.

In testimony whereof I have signed my name to this specification in the presence of two subscribing witnesses.

ELBERT J. GILMORE.
